UNITED STATES PATENT OFFICE.

WILFRED SELLERS, OF ELWOOD, INDIANA.

LATCH.

1,123,020.

Specification of Letters Patent. Patented Dec. 29, 1914.

Application filed August 12, 1914. Serial No. 856,431.

To all whom it may concern:

Be it known that I, WILFRED SELLERS, a citizen of the United States, residing at Elwood, in the county of Madison and State of Indiana, have invented certain new and useful improvements in Latches; and I do hereby declare the following to be a full, clear, and exact description of the invention, such as will enable others skilled in the art to which it appertains to make and use the same.

This invention relates to new and useful improvements in latches and has for its principal object to provide a device which is particularly adapted for use on cupboard doors and similar places where it is necessary to have a simple and efficient latch.

A further object of the invention is to provide a latch which may be entirely constructed of sheet metal and which will be particularly effective and simple in use.

Still another object of the invention is to provide a latch which not only can show the retaining of the door but will also act as a pull to enable the user to eliminate the use of a knob or similar attachment.

A still further object of the invention is to provide a latch having a minimum number of operating parts thereby reducing friction and providing a device which may be manufactured at a minimum amount of expense.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the several views, and in which:

Figure 1 is a front view in elevation of a latch constructed in accordance with this invention showing the same as it would appear when in use. Fig. 2 is a longitudinal sectional view of a latch constructed in accordance with this invention. Fig. 3 is a vertical sectional view taken on line 3—3 of Fig. 1. Fig. 4 is a detail sectional view taken on line 4—4 of Fig. 1. Fig. 5 is a view similar to

Fig. 4 showing the device in its operative position, and Fig. 6 is a face view of the base plate illustrating the detail construction thereof.

Referring now to the drawing by characters of reference the numeral 1 designates the base plate of the device which is formed with the rounded end 2. These rounded ends are provided with suitable apertures 3 which are arranged to receive the screws by means of which the device is secured in place. Formed near each corner of the plate 1 are the stamped up portions 4 which are formed with the transverse slot 5 the use of which will appear as the description proceeds. Near the upper terminal of the plate 1 and at an equal distance from the longitudinal axis thereof are provided the U-shaped slits 6 which form the ears 7 which are bent outwardly as illustrated in the drawings to form the pivot member to which the operating mechanism is secured. Formed laterally of the plate 1 are the apertures 8 which are positioned slightly below the transverse center of the plate and at equal distance from the longitudinal center thereof.

The cover member which is used in connection with this device is designated generally by the numeral 9 and comprises the face plate and which is formed with the side walls 11 and end walls 12. The end walls 12 are provided with suitable lugs which are arranged to project through the slot 5 and these lugs are then bent to firmly hold the cover plate in place. The upper end wall of the cover member 9 is provided with a slot which communicates with the slot 13 formed in the front wall 10 while one of the side walls is provided with a suitable recess 14 which is arranged to form a slot through which the latch member which will be hereinafter more fully described operates when the device is assembled.

The latch member hereinbefore referred to is designated by the numeral 15 and comprises the body 16 having formed near one end a suitable rivet receiving aperture through which the rivet 17 is arranged to extend. This rivet 17 is so arranged that it extends also through one of the apertures 8 in the base plate 1 and thus pivotally secures the latch member 15 to the base plate.

Formed centrally of the longitudinal axis of the body 16 is the rectangular aperture 18 which is so positioned as to lie at a point substantially centrally of the base plate when 5 the device is in its normal locked position.

Pivots secured to ears 7 hereinbefore referred to is the latch controlling and operating member designated generally by the numeral 19 which comprises the ring or 10 finger hold 20 which is formed with a suitable radial projection 21 this radial projection 21 is provided at its opposite terminal with a pair of spaced ears 22 which ears are spaced from each other a suitable 15 distance to enable the ears 7 hereinbefore referred to, to lie therebetween. These ears 22 and 7 are pivotally secured to each other by means of the pivot pin 23 as clearly shown in Fig. 3. Extending between the ears 20 22 near the pin 23 is a suitable pivot pin 24 which is so arranged as to pivotally secure the latch operating member 25 in operative position with relation to the member 19 hereinbefore referred to. This latch 25 operating member comprises the plate 26 which is formed at its lower terminal with the angular extension 27 this extension is arranged to project into the aperture 18 in the latch 15 and it will thus be seen that a positive connection between the latch member 30 and the latch controlling mechanism is provided. The ears 22 hereinbefore referred to are provided with a suitable cover 28 which is arranged to engage the ears 7 when the device is hanging in position illustrated in 35 Fig. 5 and thereby limit the outward movement of the member 19. It will thus be seen that a pull is provided which will automatically operate the latch and thus release the door to permit the same to be 40 swung open.

A suitable keeper designated generally by the numeral 29 is provided and this keeper comprises the base plate 30 which is formed 45 at each end with a suitable aperture 31 through which the screws for securing the device are arranged to extend. This plate is formed intermediate its ends with the extension 32 the free terminal of which is provided with an angular upstanding portion 50 behind which the latch member is arranged to engage and thereby hold the door in its closed position.

It will be apparent from the foregoing, 55 that in use the device is assembled as illustrated in Fig. 1 and the base plate 1 secured to the door upon which the device is to be used by screws or any other suitable fastening means. When it is desired to open 60 the door it will be evident that by pulling outwardly on the ring 20 the latch will be lifted from engagement with the keeper 29 through the action of the member 26 and upon further pull on the ring 20 it will be

evident that the cover plate 28 of the ears 65 22 will engage the ears 7 thereby forming a stop for the ring and eliminating the upward movement thereof which will permit the user to use the ring as a knob or pull to enable the door to be easily and quickly 70 opened. As soon as the pull is released from the ring 20 it will be evident that the latch member will return to its normal downward position through the weight of the ring and thus provide a gravity latch which will effectively hold a door in its closed position. 75

From the foregoing it will be apparent that there has been provided a simple and efficient latch which may be easily and cheaply constructed of sheet metal and assembled at a minimum amount of expense. It will also be evident that the device may be secured to any suitable article and will effectively hold the same closed to prevent 80 accidental opening thereof. 85

While in the foregoing there has been shown and described the preferred embodiment of this invention it is to be understood that such changes in the combination and arrangement of parts as may fall 90 within the scope of the claims may be resorted to without departing from the spirit and scope of the invention. 95

Having thus described the invention what is claimed is:—

1. A latch including a casing, a latch member pivotally secured within the casing, the free end of the latch member projecting beyond one of the lateral extremities of the casing said latch member being provided with a rectangular aperture near its pivoted end, a latch controlling member pivoted within the casing near the upper end thereof a link pivotally secured to the latch controlling member and eccentric with relation to the pivot point of the latch controlling member and an angular projection at the free terminal of the link, said angular projection being arranged to extend into the rectangular aperture in the 110 latch member whereby upon movement of the latch controlling member the latch member will move. 105

2. A latch including a base plate, ears formed on the base plate near its upper extremity, a casing secured to the base plate, one of the side walls of the casing being cut away to form a slot between the casing and base plate the front and top wall of the casing being cut away to form a slot, a latch 115 controlling member, said latch controlling member comprising a ring, a stem formed on the ring, ears projecting angularly from the opposite terminal of the stem, said ears being pivoted to the outer faces of the ears 120 on the base plate, a cover member secured to the base plate, said cover member limiting the outward swing of the ring, a latch 125

member pivoted to the base plate, said latch member extending through the slot formed between the base plate and the casing and a link pivoted between the ears on the latch 5 controlling member at a point distant from the pivot point thereof, said link projecting between the ears on the base plate and connected to the latch member whereby

upon movement of the latch controlling member the latch member will be operated. ¹⁰

In testimony whereof I affix my signature in presence of two witnesses.

WILFRED SELLERS.
